(57) **CLAIM**

The ornamental design for the aircraft sidearm controller, as shown and described.

DESCRIPTION

FIG. 1 is a right front top isometric view of the aircraft sidearm controller, showing our new design;

FIG. 2 is a top plan view of the aircraft sidearm controller; FIG. 3 is a front elevation view of the aircraft sidearm controller, enlarged for ease of illustration;

FIG. 4 is a right side elevation view of the aircraft sidearm controller;

FIG. 5 is a back elevation view of the aircraft sidearm controller, enlarged for ease of illustration; and,

FIG. 6 is a left side elevation view of the aircraft sidearm controller.
